CORNICE FOR WINDOWS

Harry Derman, Laurelton, Long Island, N. Y.

Application December 1, 1941, Serial No. 421,110

3 Claims. (Cl. 169—21)

This invention relates to what is commonly known as a cornice used in trimming the interior of windows primarily to cover and conceal curtain rods, drapery supports and the like in producing a neat and attractive appearance; and the object of the invention is to provide a device of the class described comprising detachable and adjustably coupled parts so constructed as to provide a compact packaging of the parts in a container in a package of minimum size, a further object being to provide a cornice employing supporting brackets of strong and durable construction with means on the brackets and on telescoping rails of the cornice for detachably coupling the rails with the brackets without the use of fastening devices of any kind, a still further object being to provide a cornice of the character described minimizing the use of hardware parts, while at the same time providing a cornice which can be painted or otherwise finished by the purchaser to suit or harmonize with the room in which the cornice is to be mounted, and with these and other objects in view the invention consists in a device of the class and for the purpose specified which is simple in construction, efficient in use and which is constructed as hereinafter described.

The invention is fully disclosed in the following specification, of which the accompanying drawing forms a part, in which the separate parts of my invention are designated by suitable reference characters in each of the views, and in which:

Fig. 1 is a perspective view of the upper portion of a window illustrating one of my improved devices mounted thereon.

Fig. 2 is a partial section on line 2—2 of Fig. 1.

Fig. 3 is an end view of the central portion of a cornice showing a modification.

Fig. 4 is a view similar to Fig. 3 showing another modification and also indicating one of the rails in section.

Fig. 5 is an exploded perspective view of one bracket and the coupled end portion of one of the rails; and

Fig. 6 is a diagrammatic view illustrating the packaging of the parts in a container, the parts being those shown in Figs. 1, 2, and 5 of the drawing.

In the construction of cornices of the type and kind under consideration, for the most part these cornices have been expensive in construction and quite often made to measure, which has also materially added to the cost thereof, thus devices of this type and kind have been limited in use as they have been beyond the reach of the average consumer. It is the purpose of my invention to provide a device of this type and kind, which is extremely economical in its construction and further which is so made that a production of two sizes of these devices would care for all in-

stallations by virtue of the degree of adjustability of the parts one with respect to the other. Thus it is possible to accurately or properly apply the cornice to any desired installation. At this time, 5 it is well to mention that even in the small size of the adjustable unit, the cornice may be as narrow as the central rail of the assemblage by simply sawing off and shortening the inner adjacent ends of the rail parts which telescope therewith, so that the outer coupling ends of the adjustable rails can be brought into abutting engagement with the ends of the central rail. Still further, the cornice is so constructed that the several parts can be compactly packed in an 10 elongated box or container or simply wrapped in a package the dimensions of which are governed by the length and width of the central rail and the height of the parts as arranged snugly one upon the other. It will also be apparent that by producing the cornice in unfinished wood, the purchaser may then paint, stain, varnish or otherwise finish the surfaces of the 15 various parts of the cornice to suit and harmonize with the room in which the same is to be supported.

In Figs. 1, 2, 5 and 6 of the drawing, I have shown one adaptation of the invention. In these figures, the cornice comprises a central channel rail 10, in connection with which are slidably and adjustably mounted rails 11 and 12, which fit in the channel 13 of the rail 10 and are held against displacement from the channel by transverse strips 14 secured to the inner surface of the upper and lower flange portions 15 of the rail 10 and these strips are clearly illustrated in Fig. 2 of the drawing. At this time, it is also well to note that these strips are so positioned on the rail 10 as to provide interlocking of the end strips 14 with the brackets 16 in packaging the parts 30 as seen in Fig. 6 of the drawing, said strips 14 entering vertical recesses 17 in said brackets.

The outer surfaces of the rails 10, 11 and 12 are grooved or otherwise characterized for ornamental purposes the groove forming corresponding ribs and it is preferred that in viewing the rails directly at the front thereof, that these grooves be in common alinement on all of the rails.

Each of the rails 11 and 12 are of the same construction, though one rail becomes a right hand rail and the other a left hand rail by virtue of the coupling blocks or plates 18 on the ends of these rails. These blocks are of the same construction, however, and will include downwardly directed recesses 19 centrally thereof, which are adapted to receive the web member 20 in the recessed portion 17 of the brackets 16. In providing a tongue and groove coupling between the blocks 18 and said brackets 16 upper edges of the brackets 16 in alinement with the 35 40 45 50 55 60

side recesses 17 is cut out or recessed as seen at 21, note Fig. 5 of the drawing to receive the body portion of the block 18. In other words, the width of this recess corresponds to the thickness of the block to provide a free but yet snug fit of the blocks in the brackets thus maintaining the cornice in a substantially rigid position when installed.

The transverse dimensions or width of the blocks 18 correspond to the width of the outer end portions of the bracket 16 so that the outer ends 22 of the brackets form upon the outer surfaces of the blocks 18 vertical columns which finish and ornament the ends of the cornice. Where other ornamental effects are desired, the brackets can, of course, be modified in construction and this is also true of the outer ends of the coupling blocks 18.

The inner or attaching ends of the bracket 16 terminate in upwardly and downwardly extending apertured flanges 23 through which screws, nails, or other devices are passed in attaching the brackets to suitable support. For example, to the frame 24 of a window 25 as partially indicated in Fig. 1 of the drawing. The brackets will be so arranged upon the window as to position the rails in front of curtain rods or other hanging means to conceal the same and to form a neat and finished appearance at the upper end of curtains, drapes or other window or door trimmings.

It is also preferred that upper and lower ends of bracket 16 taper inwardly as seen at 26, note Fig. 5 of the drawing, in order to provide a clearance for the free operation of a screw driver or other tool in mounting the brackets in position, while at the same time, minimizing the total width of the bracket. In this way, the width of the bracket is kept within the width of the wider central rail 10.

In installing the cornice and after the rail parts have been properly adjusted, with the center rail 10 centralized on the rails 11 and 12, the inner surfaces of the rails 11 and 12 may be marked with respect to the two end strips 14. The rails may be then detached from the brackets and nails or other fasteners applied to the inner surfaces of the rails 11 and 12 adjacent or through end strips 14 which will retain the strips in the desired position of adjustment. Then the complete rail unit may be attached and detached with respect to the brackets at will without disturbing the relationship of the several rails.

In packaging the various parts of the cornice in two telescoping box parts indicated in dot and dash lines at 27 and 28, Fig. 6 of the drawing, the rails 11 and 12 are disposed one upon the other with ends of one rail abutting the coupling blocks of the opposed rail as indicated in said figure.

In constructing the bracket 16, it is preferred that the flanges 23 constitute ends of a strip 29 glued and otherwise secured to the body portion of the bracket in order to give strength to these flange ends and in like manner a dowel pin or other reinforcing element 30 may be passed through the ends 22 into the webs 20 to reinforce the ends 22 from stresses or strains to which they may be subjected in coupling and uncoupling the blocks or plates 18 therewith.

In Fig. 3 of the drawing I have shown a slight modification in the construction of the center rail. In this figure 31 represents the channeled rail, 32 the channel in the rear surface thereof. 5 This channel is formed by L-shaped strips 33 secured to the inner surface of the rail 31 at upper and lower edges thereof by screws, nails or other devices. The flange portions 34 of the strips 33 project inwardly and form thereof retaining flanges which will retain the telescoping rails against displacement from the channel 32 in the same manner as the transverse strips 14.

In Fig. 4 of the drawing is shown another modified form of center rail which may be employed. With this construction the rail 35 is provided with a dove-tail channel 36 on the inner surface thereof, formed by undercut flanges 37 at upper and lower edges of the rail. These undercut flanges provide bevelled surfaces 38 opening into the channel 36. With this construction, the telescoping rails, one of which is indicated at 39, in Fig. 4 of the drawing, will have corresponding bevelled upper and lower edges 40 to fit the bevelled surfaces 38 in guiding the rails in their sliding movement in the channel 36 of the center rail.

Having fully described my invention, what I claim as new and desire to secure by Letters Patent is:

30 1. In a cornice of the class described, brackets for supporting the terminal ends of the rail portion of the cornice, said brackets each comprising a thin plate like body, the inner mounting end of said body having projecting apertured 35 lugs, the outer end portion of said body having vertical recesses on opposite side surfaces thereof forming a vertical column at said end of the plate and the upper edge portion of the plate inwardly of said column, and in alinement with 40 said recesses being cut out to form a channel adapted to receive the terminal end of the rail portion of said cornice.

2. An adjustable knockdown cornice, comprising a center rail, end rails adjustable with respect 45 to end portions of the center rail, means keying the end rails against displacement from the center rail apart from the sliding engagement between said rails, outer ends of said end rails having grooved coupling plates, brackets for mounting the cornice on a support, said brackets having rail keying sections with which the grooved end plates are coupled, and said keying sections comprising grooves in one end and at 50 least one side of said brackets for keying the end rails against movement when supported on said brackets.

3. A cornice of the class described comprising a center rail, said rail having common parallel upper and lower flanged edges, end rails slidably 60 engaging the center rail, means including said flanges on the center rail engaging the end rails to maintain the rails in coupled and alined relationship, means including plates at outer end portions of said end rails for mounting the same upon suitable supports, said last named means comprising flat plate like brackets having inner mounting ends and outer rail keying ends, and said keying ends of the brackets having grooves opening through one end and one side surface thereof.

HARRY DERMAN.
